UNITED STATES PATENT OFFICE.

FRIEDEMEN R. JAEGER, OF OAK PARK, ILLINOIS.

TIMING MECHANISM.

1,310,702.

Specification of Letters Patent.

Patented July 22, 1919.

Original application filed June 14, 1918, Serial No. 239,915. Divided and this application filed August 24, 1918. Serial No. 251,299.

To all whom it may concern:

Be it known that I, FRIEDEMEN R. JAEGER, a citizen of the United States, residing at Oak Park, in the county of Cook and State 5 of Illinois, have invented certain new and useful Improvements in Timing Mechanisms, of which the following is a specification.

My invention relates to timing appliances, such as are suitable and desirable for employment with various mechanisms, for example, clothes washing machines, whereby the operator may be advised when the cleansing operation has proceeded sufficiently and the clothes are ready for further treatment. To this end, the timing mechanism is connected directly to the power-transmitting means or driving-shaft of the washing machine which may be of the reversing type, that is to say, it may be equipped with 10 an oscillatory cylinder which rotates in one direction a predetermined number of revolutions and then automatically reverses its direction of movement and completes the same number of revolutions in such opposite direction, whereupon it again reverses and continues this operation until stopped by the operator. Machines of this style ordinarily have a double clutch mechanism associated with a main drive shaft constantly 15 rotated in one direction, and the improved timing device is driven by such main shaft so that it always works in the same direction regardless of which clutch is active and regardless of the reversals of movements of 20 the cylinder. The timing device is properly graduated and has an index readily returned to zero position, and, inasmuch as the washing machine is ordinarily driven by a practically constant-speed electric-motor, the timing appliance may be graduated in minutes and fractions thereof.

In order that those skilled in this art may have a full understanding of the structural features of this invention and the functional advantages accruing therefrom, I have illustrated in the accompanying drawing, forming a part of this specification, and throughout the various views of which like reference characters refer to the same parts, a preferred and desirable embodiment of the invention associated with the operating mechanism of a washing machine.

In this drawing:

Figure 1 is an elevation showing the reversing driving mechanism for the cylinder

of the washing machine in association with the timing appliance, the electric-motor being shown fragmentarily;

Fig. 2 is a face view of the timing device; and

Fig. 3 is a fragmentary section through the central portion of the same.

The improved appliance is driven by a constant-speed electric-motor 10 operating a shaft 11 provided with two oppositely-facing bevel pinions 12 and 13, both constantly in mesh with a larger bevel-gear 14 connected to and driving an oscillatory clothes-containing drum or cylinder, not shown. Operatively associated with these pinions is a double-clutch mechanism 15, 16, adapted to render either pinion active by connecting it to shaft 11 by reason of the inter-engagement or meshing of the usual clutch-teeth, the duplex clutch appliance being controlled 60 or actuated by a lever or handle 17 fulcrumed at 18, and which, when in upright or neutral position, holds both clutches inactive or inoperative. When the handle is swung to the right, clutch 15 becomes operative 65 and the clothes drum or cylinder is revolved in one direction, and when the handle is shifted to the left, such clutch connection is broken, the other one, 16, being rendered active, and the drum or cylinder is rotated 70 in the opposite direction. Such shifting clutch action ordinarily occurs entirely automatically, as set forth, for example, in my United States Patent No. 1,252,698, mechanical movements, granted January 8, 75 1918, whereby the cylinder is rotated a definite or predetermined number of revolutions in one direction and then the same number in the opposite direction, and this action is automatically maintained or continued until manually terminated by holding or stopping the lever or handle in neutral or midway position.

The timing mechanism proper is inclosed within a casing 20 and comprises a shaft 21 80 having a notched end 22 accommodating a tongue 23 on the end of shaft 11, such slot and tongue comprising a positive and direct driving connection. Shaft 21 has a worm 24 coacting with a worm-wheel 25 on a shaft 26 85 rotatably supported in the housing, which shaft in turn has a worm 27 meshing with a worm-wheel 28 on a hollow shaft 29 revoluble in suitable bearings 30 and 31. This hollow shaft has an inclined disposition and 90 105 110

its upper end has fixed thereto a notched disk 32, (Figs. 2 and 3), whose periphery is provided with 12 notches, each corresponding to a period of five minutes. The hollow shaft 29 has within it a solid shaft or rod 33 equipped outside of the casing or housing with a thumb piece or knob 34 and a pointer or index finger 35 equipped on its under side with a lug or pin 36 adapted to enter any one of the notches of disk 32. The knob and index are rigid with and necessarily rotate with the solid inner shaft and all through with the outer hollow shaft when the lug is in the notch of the disk, such lug and disk representing a driving clutch connection. The pointer or index and its turning thumb piece 34 to which it is rigidly fastened, are held against the face of the casing or housing by means of a spring 37 bearing at one end against the end of the hollow shaft and at the other end against a head 38 on the rod or solid shaft 33. This permits a temporary raising or lifting of the knob and the pointer so that the latter may be shifted or turned back to zero position, the lug beneath it dropping into another notch and being held therein by reason of the action of the spring as soon as the knob is free from the hand of the operator. As is clearly shown in Fig. 2, the face of the cover 39 for the timing mechanism feature is supplied with a circular graduated scale 40 with which the pointer coöperates, such scale being divided into 60 parts representing minutes, the five minute graduations being more conspicuous than the others.

Before the appliance is set in operation, the operator lifts the knob 34 and its associated pointer or index and turns the latter back to or substantially to zero position, whereupon the pin 36 springs into the corresponding notch of the disk. Then as the mechanism operates, the finger or pointer 35 travels over the dial quite slowly, its movements being so timed with relation to the speed of the motor that the graduations or markings of the scale with which it coöperates represent minute periods.

When the washing machine or other mechanism with which the clutch device and timing mechanism are associated has been actu-

ated the desired period, as shown by this finger 35, the mechanism is stopped, and then the pointer may be returned to or substantially to zero position, ready for indicating the period of the next operation. It will be observed that since this timing device is directly connected to the shaft 11 and since such shaft always rotates in the same direction regardless of the oscillatory movement of the clothes cylinder, the period of rotation of the shaft, that is, the length of time the main device operates, is at all times indicated on this timing mechanism regardless of the various automatic shiftings of the clutch mechanism.

To those skilled in this art it will be clear that many minor mechanical changes may be made in the apparatus illustrated and described without departure from the substance and principle of the invention and without the sacrifice of any of its substantial benefits and advantages.

This application is a division of my earlier application for improvements in clutches, Serial No. 239,915, filed June 14, 1918.

I claim:

In a time-indicating appliance of the character described, the combination of a hollow shaft, a bearing for said shaft, means to rotate said shaft at a substantially-uniform speed, a notched-disk mounted on and revoluble with said shaft, a second shaft slidable in and adapted to be turned relatively to said hollow shaft, a knob mounted on said inner shaft by which the latter may be manipulated, an index mounted on and revoluble with inner shaft, a stationary scale graduated in intervals of time with which said index coöperates, a lug on said index adapted to enter any of the notches of said disk and complete a driving connection between said shafts, said lug and notched disk constituting the sole driving connection between said shafts, and a spring acting on said inner shaft yieldingly holding said lug in the notch, permitting withdrawal thereof and the manual return of the index to zero or substantially zero position, substantially as described.

FRIEDEMAN R. JAEGER.
